CLAIM

The ornamental design for a chair, as shown and described.

DESCRIPTION

FIG. 1 is a perspective view of my new design of a chair;

FIG. 2 is a front view of my design shown in FIG. 1;

FIG. 3 is a rear view of my design shown in FIG. 1;

FIG. 4 is a left-side view of my design shown in FIG. 1;

FIG. 5 is a right-side view of my design shown in FIG. 1;

FIG. 6 is a top view of my design shown in FIG. 1; and,

FIG. 7 is a bottom view of my design shown in FIG. 1.

The ornamental design which is claimed is shown in solid lines in the drawings. The broken lines are for environmental purposes only and do not form any part of the claimed design.

1 Claim, 6 Drawing Sheets
